UNITED STATES PATENT OFFICE.

THEODOR FREY, OF HOCHDORF, SWITZERLAND.

LIFTING MECHANISM FOR STAMP-MILLS AND THE LIKE.

1,086,151.

Specification of Letters Patent.

Patented Feb. 3, 1914.

Application filed May 7, 1913. Serial No. 766,243.

To all whom it may concern:

Be it known that I, THEODOR FREY, a citizen of the Republic of Switzerland, residing at Hochdorf, in the Canton of Lucerne, Republic of Switzerland, have invented certain new and useful Improvements in Lifting Mechanism for Stamp-Mills or the like; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The present invention has for its object to provide an improved lifting mechanism for stamp mills or the like. This apparatus is provided with a clamping frame constantly moving up and down and with a brake automatically preventing the free falling of the bars.

One embodiment of this invention is illustrated by way of example in the accompanying drawing.

Figure 1 is a side view of the apparatus, Fig. 2 shows the clamping frame partly in a side view taken from the left in Fig. 1, partly in section. Fig. 3 is a plan view of the brake. Fig. 4 is a detail showing the manner of mounting certain of the elements described below.

The bar *c* to be lifted and let fall is mounted in two guides *a* and *b* so that it may be moved upward and downward with its axis in vertical position. Each of these guides is provided with a laterally extending arm to which one end of a vertical rod *d* is firmly attached. To this rod *d* a stop *e* is fastened projecting toward the bar *c* and below this stop the rod *d* is provided with a bearing-arm *f* extending on the opposite side of the rod. An angular lever *g*, one end of which projects away from the rod *d*, is pivotally mounted on the bearing-arm *f*. Above its knee the angular lever *g* is provided with a stop pin *h* extending through the bearing-arm *f* and the rod *d* and constantly held in the path of a nose *k* by means of a spring *i*. In Fig. 1 the dotted line position of nut *K* shows the latter engaging pin *h*. One end of the spring enters the pin and the other end is secured to bar *d*. The nose *k* is provided on a screw-nut *k* connecting the two parts of a two-parted screw-spindle *j*, *j*'. One of these parts

has a right-handed, and the other a left-handed thread so that when the nut *k* is turned in one or the other direction the part *j* is moved to and fro in axial direction. 60 The part *j* is provided on its free end with a clamping plate *m* projecting through a slot *m*² the wall of a guiding piece *m*¹ which surrounds the bar *c* and forms part of a clamping frame *n*. This frame is suspended, by means of rods *n*¹, to a rotary crank (not shown) so that it is constantly moved up and down. The part *j*' of the spindle *j* *j*' is provided on its free end which projects out of the nut *k*, with a wedge shaped head 70 *j*². A wedge *o*¹ is provided between this head and the frame *n* and adapted to be moved in a vertical dovetail groove in said head by means of a screw *o* mounted in the frame *n*. By moving the wedge *o*¹ the action of the clamping plate *m* can be regulated. Below the clamping frame *n* the bar *c* is embraced by two brake-blocks *p* which normally rest on the bearing *b*. On two points placed one above the other each of 80 said blocks *p* is connected, by means of a bow *q*, with two levers *r* one on each side of the bar *c*, in such a manner, that when the lever *r* oscillates up and down the brake-blocks *p* strongly embrace and release the 85 bar *c* alternately. The releasing takes place however only in such a manner that the brake-blocks are always in contact with the bar so that they are able to embrace them strongly and immediately when the bar 90 sinks so that they may prevent automatically the bar from falling.

The levers *r* are connected on their other ends to the free ends of a strap *s* oscillating upward and downward about a stationary 95 axle *t*. A vertical rod *u* is pivoted at its upper end to the middle-part of the strap *s* and with its lower end to a hand-lever *v*. This hand or regulating-lever effects by its own weight a constant raising of the levers 100 *r* and applying of the brake-blocks to the bar *c*.

The operation of the described apparatus is as follows: As it was already said the frame *n* is continually moved up and down. 105 In order to raise the bar *c* for a desired extent, the pin *h* is placed in the path of the nose *k*¹ so that in the lowest position of the frame *n* the screw-nut *k* is turned to the right (Fig. 1) and consequently the bar *c* is 110 clamped in the guide *m*¹. At the next upward-movement of the frame *n*, the bar *c*, on

which a rammer or the like may be provided, is lifted. When the nose k^1 strikes the projection e , the screw-nut k is turned back and the clamping-plate m moved away from the bar c . This at once tends to fall but is prevented therefrom by the brake-blocks p as these are at once forced against the bar c . The latter rests therefore in its raised position during the next downward movement of the brake-frame n and is raised for the same extent at the next upward movement of the latter as set forth.

If it is desired to let fall the bar c after each upward stroke, the brake-blocks p are put out of action by raising the lever v . If the bar c shall be moved up and down with the frame n but not be raised and let fall alternately, the angle-lever g is raised by means of a rod w hinged thereto and secured in this raised position by means of a thumb-screw x . By this means the bolt h is kept out of the path of the nose k^1 of the screw-nut k and therefore the bar c is not released from the clamping plate m but after the screw-nut k is turned back again. By regulating the position of the lever v the speed of the bar c in falling may be increased or decreased.

What I claim is:—

1. In a device of the class described, a bar to be reciprocated, a reciprocating frame for operating said bar, rotary clamping mechanism within the frame including members having reverse threads and means for operating said member by the reciprocation of the frame.

2. In a device of the class described, a bar to be reciprocated, a reciprocating frame, a threaded member within the frame for engaging the bar, a second threaded member, the threads of the latter being arranged in the opposite direction to those of the former, a nut engaging said members, and means for rotating the nut.

3. In a device of the class described, a reciprocating frame, a bar to be reciprocated by the frame, a clamping member in the frame, a threaded member connecting with the clamping member, a second member having a thread extending in the opposite direction, means for adjusting the second member, and a nut having threads reversely arranged engaging the threaded members and means for operating the nut to move the clamping member into engagement with the bar.

4. In a device of the class described, a reciprocating frame, a bar to be reciprocated thereby, means carried by the frame and within the same for positively engaging the bar, means for causing said means within the frame to be operated and a device for throwing the means last mentioned out of action.

In testimony whereof, I have signed my name to this specification in the presence of two subscribing witnesses.

THEODOR FREY.
